UNITED STATES PATENT OFFICE.

HINRICH B. SCHUTT, OF BROOKLYN, NEW YORK.

STRUCTURAL METAL-WORK IN BUILDINGS.

No. 893,815.

Specification of Letters Patent.

Patented July 21, 1908.

Application filed February 18, 1907. Serial No. 357,834.

To all whom it may concern:

Be it known that I, HINRICH B. SCHUTT, a citizen of the United States, and resident of Brooklyn, county of Kings, and State of New York, have invented certain new and useful Improvements in Structural Metal-Work in Buildings, of which the following is a specification, reference being had to the accompanying drawing, forming a part thereof, in which similar letters of reference indicate corresponding parts.

This invention relates to structural metal-work of the character employed in constructing steel or iron-frame buildings; the objects thereof being to provide parts to be employed in structures of this character which are of such novel formation as to be interlocked and assembled without the necessity of using either rivets or bolts and nuts, whereby the process of constructing an iron or steel-frame building comprising a plurality of such parts is greatly facilitated and the cost of the structure is considerably lessened.

The invention will be hereinafter fully described and specifically set forth in the annexed claims.

In the accompanying drawings forming part of the specification, Figure 1, is a perspective view of a lateral beam forming part of my invention; Fig. 2, an end elevation of a part of a cross-beam having one of the said lateral beams coupled thereto; Fig. 3, a vertical sectional elevation taken on the line 3—3, of Fig. 2; Fig. 4, a sectional plan view taken on the line 4—4, of Fig. 3; Fig. 5, a similar view showing a double-coupling; Fig. 6, a side elevation, shown partly in section, illustrating the application of my invention as a means for coupling horizontal beams to a vertical column; Fig. 7, a perspective view of the end of a horizontal beam; Fig. 8, a sectional plan view showing three horizontal beams in position partially connected, and Fig. 9, is a perspective view of part of a vertical column.

In the examples of my invention shown by the drawings A, illustrates the lateral beams and B, the main or cross-beams. The beams A, are provided at each end with a tongue 1; the said tongues being extended at right angles from and formed integral with the stem a, of the beam A, the flanges of said beams being cut away as shown. The said tongues are extended in opposite directions and approximately at right angles from the said stem a, and they may be of any desir-

able proportion, each being provided on its under side and near the point of intersection with the stem a, with a notch 2, for engagement with a part of the stem of an adjacent beam, as will be hereinafter described.

The beams B, are provided with horizontal pockets 3, formed integral with their stems b, and vertical slits 4, adjacent thereto. Where two lateral beams A, are to be connected to a main beam B, as shown by Fig. 5, of the drawings, double pockets 5, are provided, having a slit 6, located between them, the same being formed integral with the stem b, one on each side thereof. When a horizontal beam, as C, Figs. 6 and 7, is to be connected to a vertical column or post, as D, the latter is provided with vertical pockets 7, and adjacent slits 8; and the horizontal beams, as C, are provided with downwardly extended tongues 9, which are formed integral with and extend approximately at right angles from the flanges 10; the stems c, being cut away as shown. The pockets of the stems b, are sufficiently deep to snugly accommodate the tongues 1, whereby they register with said stems; and they are sufficiently high to allow the said tongues to freely enter during the operation of assembling the parts.

In assembling a structure, two cross-beams B, being placed with their pockets 3, opposite to each other, a beam A, is swung between them as shown in Fig. 8, of the drawings, then the same is forced into position at right angles relative to the beams B, as shown by Fig. 4, of the drawings, with the pockets and tongues in snug engagement. Afterwards the beam A, is driven downwardly until its notches 2, engage the stem-parts of the beam B, immediately beneath them, whereby the main and lateral beams are securely locked together, and gravity holds the beam A, in place and liability of lateral displacement is obviated; thus secure assembling of beams at right angles to each other is effected without the aid of straps, brackets, rivets or nuts and bolts. The horizontal end beams of a structure are also readily connected to their adjacent uprights without the aid of supplementary means for fastening as shown by Fig. 6, of the drawings. By this mode of construction a whole metallic frame work of a building may be quickly and economically assembled.

I do not confine myself to specific forms of the parts nor details of construction as here-

in shown and described, as it is obvious that under the scope of my invention I am entitled to variations which may be required, by different structures, as will be apparent to those 5 familiar with the art of constructing framework of the character named.

Having thus described my invention, what I claim as new and desire to secure by Letters Patent, is:—

- 10 1. In structural metal-work, the combination with a part having pockets and slits adjacent to said pockets and leading into the said pockets at right angles therewith, and beams having notched end tongues extending at right angles thereto, the said tongues engaging the said pockets and when in such engagement extending parallel therewith, substantially as shown and described.
- 15 2. In structural metal-work for buildings, the combination with beams having horizontal pockets in their stems and vertical slits adjacent to said pockets, of beams at right angles therewith and having tongues engaging said pockets and extended parallel therewith, substantially as shown and described.
- 20 3. In structural metal-work for buildings, the combination with beams having pockets in their stems and slits adjacent to said pock-

ets, of beams having tongues engaging said 30 pockets, the said tongues having notches engaging over parts of the stems, substantially as shown and described.

4. As a new article of manufacture to be employed as a part of a metallic frame-work 35 of a building, a metallic beam having end tongues at each end thereof, extending in opposite directions at right angles thereto, and by reason of their construction and arrangement affording facility for engaging 40 pockets in the beams next adjacent thereto, substantially as shown and described.

5. As a new article of manufacture to be employed as a part of a metallic frame-work 45 of a building, a metallic beam having end tongues at each end thereof, extending in opposite directions and at right angles thereto, said tongues having each a notch therein, substantially as shown and described.

In testimony that I claim the foregoing as 50 my invention, I have signed my name in presence of two witnesses, this 11th day of February 1907.

HINRICH B. SCHUTT.
